Attorney

UNITED STATES PATENT OFFICE.

ALVA A. CRESS, OF DETROIT, MICHIGAN,

WRENCH.

Application filed February 1, 1922. Serial No. 533,245.

To all whom it may concern:

Be it known that ALVA A. CRESS, a citizen of the United States of America, residing at Detroit, in the county of Wayne and

5 State of Michigan, has invented new and useful Improvements in Wrenches, of which the following is a specification.

The object of the invention is to provide a wrench having an adjustable jaw with 10 means for readily and efficiently locking the movable jaw in its adjusted positions to prevent variation in the position thereof either toward or from the object interposed between the jaws and thereby minimize the 15 tendency of the wrench to slip around the ankles of nut and bolt heads particularly when the latter are of relatively soft material; and with this object in view the invention consists in a construction and combination 20 of parts of which a preferred embodiment is shown in the accompanying drawings, wherein:—

Figure 1 is a side view of a wrench embodying the invention.

25 Figure 2 is a detail sectional view of a portion of the same.

The wrench embodies essentially a shank 10 having a fixed outer head 11 and a movable head 12 provided with a slide 13 fitted 30 for adjustment upon the shank and movable toward and from the fixed jaw, said movable jaw being adjustable by means of a knurled screw 14 revolvably mounted upon a fixed spindle 15 carried by the movable jaw and 35 engaging a rack 16 on the shank.

The adjusting screw is exposed for access 40 to the fingers of the operator in a cut-away portion 17 of the movable jaw between shoulders 18 and 19 of which the spacing is somewhat greater than the length of the adjusting screw, and the spindle 15 is threaded as indicated at 20 for engagement with an opening 21 in the inner end of the jaw and also for engagement by a lock nut 22 which 45 is adapted for adjustment into frictional engagement with the inner end of the adjusting screw 14. Therefore after an adjustment of the movable jaw to the proper interval from the fixed jaw to engage an interposed jaw, the lock nut, which is of slightly less diameter than the adjusting screw but is located at the inner end thereof may be turned up against the inner end of the adjusting screw by a continuation of the

movement of the fingers which serves to adjust said screw, to lock the latter and therefore the movable jaw in its adjusted position.

The coaxial and adjusting relation of the 55 adjusting screw and locking nut, in other words, provides for an adjustment of the jaw and a locking of the latter in the adjusted position practically by a single movement of the thumb and forefinger of a hand 60 grasping the shank, so that while there is no loss of time involved in the adjustment of the wrench to the object to be grasped, the 65 jaw is secured against displacement during the continuance of the work which necessitates that particular adjustment.

The lock nut 22 when in engagement with the adjacent screw 14 may be moved into 70 abutting relation with the shoulder 19 and thus lock the spindle in place to preclude its working out due to the handling of the 75 wrench and the rotation of the threaded portion in the internally threaded opening 21. When the lock nut is engaged with the adjusting screw, the latter is forced against the shoulder 18 and since the lock nut is 80 engaged with the threaded portion of the spindle the latter is precluded from any change of position due to angular movement 85 due to the engagement of the screw 14 of the shoulder 18 and the lock nut with the screw 14.

Having described the invention, what is claimed as new and useful is:—

A wrench having a shank provided with 90 a rigid jaw, a movable jaw mounted to slide upon said shank and cut away to provide spaced shoulders between which is exposed a rack formed on the shank, a spindle spanning said shoulders and having a threaded portion engaging an interiorly threaded hole 95 communicating with one shoulder, an adjusting screw slidably mounted on the spindle and engaged with the rack on the shank, and a lock nut carried by the threaded portion of the spindle and movable into abutting engagement with the adjacent shoulder or into abutting engagement with one 100 end of the adjusting screw to force the latter into contact with the remaining shoulder in the manner and for the purpose specified.

In testimony whereof he affixes his signature.

ALVA A. CRESS.
